(57) **CLAIM**

I claim the ornamental design for a personal alarm, as shown and described.

DESCRIPTION

FIG. 1 is a top perspective view of a personal alarm of the present application, those elements shown in broken line are for purpose of illustrating environment only and form no part of the claimed design;

FIG. 2 is a bottom perspective view of a personal alarm, those elements shown in broken line are for purpose of illustrating environment only and form no part of the claimed design;

FIG. 3 is a left side elevational view of the personal alarm;

FIG. 4 is a top plan view of the personal alarm; and

FIG. 5 is a bottom plan view of the personal alarm.

FIG. 6 is a front elevational view of the personal alarm;

FIG. 7 is a rear elevational view of the personal alarm; and, FIG. 8 is a right side elevational view of the personal alarm.

Note 1: In the drawings, the cord shown in broken lines is for the purpose of illustrating environment only and forms no part of the claimed design.
